UNITED STATES PATENT OFFICE.

T. GARDNER ELLSWORTH, OF NEW YORK, N. Y.

TELEPHONE SWITCH-BOARD.

SPECIFICATION forming part of Letters Patent No. 226,991, dated April 27, 1880.

Application filed December 30, 1879.

To all whom it may concern:

Be it known that I, T. GARDNER ELLSWORTH, of the city, county, and State of New York, have invented a new and useful Improvement in Telephone Switch-Boards, of which the following is a specification.

Figure 1 is a front elevation of a switch-board, partly in section, showing my improvement disconnected from the main-line wires. Fig. 2 is a front elevation of the same, showing the position of the rods when making connection between different wires of the main line. Fig. 3 is a vertical sectional end elevation on line *x x*, Fig. 1. Fig. 4 is a longitudinal section on line *y y*, Fig. 1.

Similar letters of reference indicate corresponding parts.

The object of this invention is to facilitate the connection and disconnection of different telephone and telegraph lines at a central office.

The invention consists of a suitable board carrying one or more movable indicating conducting-rods, with which the telephone or telegraph wires connect, said rods serving not only to connect the wires, but also to indicate by their position when they are in use and when they are unoccupied.

In the drawings, A represents the board for supporting the switch-rods. B B are the vertical braces or supports holding the rods in position upon the board A. C is a round rod provided with pin-holes *a*, and connected at one end by the wire F with a telegraph-instrument or telephone.

On the board A, above the said switch-rod C, are seen the main-line-wire switches K L M, with the wires R S T, respectively, connected with them, which latter indicate the termini of the main-line wires.

This apparatus is intended to be used more especially in connection with a number of main-line wires which are to be put in connection with one another.

Part of the apparatus used in this connection consists of two switch-pins, N N, coupled together by a flexible conducting-wire, O, several pairs of these coupling-pins being ordinarily in use.

The operation of this device is as follows, when used in connection with telephone lines and in-

struments: When an annunciator in rear of one of the main-line switches—for example K—announces at a central office that some one on the main line R wishes to communicate with a person on another main-line wire, one of a pair of coupling or switch pins, N, is inserted in one of the pin-holes of the switch-rod C, and the other coupling-pin of that pair is inserted in a hole in that main-line-wire switch through which the announcement has come—for example, switch K, Fig. 2—and by this means communication is immediately established between the person wishing to communicate and the operator who has charge of the switch-board, 55 by means of the current which passes from the main-line wire through the switch K and coupling-pins N and their connecting-wire O, and thence, through the switch-rod C and its end wire, F, to the telephone, which is placed in a 60 convenient position for the use of the operator.

The operator then learning by means of the telephone-instrument with whom the communicating party from switch K wishes to converse—the wire T, for example, leading to such 65 party from the switch M in Fig. 2—the operator takes another pair of wire-connected coupling-pins, N, and inserting one of the said pins in a pin-hole in the rod C, places the other pin N of the last couple or pair in a pin-hole in 70 the main-line-wire switch M with which is connected the wire T, through which communication may be made with the person indicated; and on making this last connection of the coupling-pins N with the switch-rod C the 75 operator revolves the said rod so that the row of pin-holes *a a* will be turned uppermost, as shown in Fig. 2, instead of showing on the face of the said rod, as seen in Fig. 1, and this position of the said rod C, which may be seen 80 at a glance, indicates that the rod is in use, and consequently that other messages cannot be transmitted through it until the said rod has been restored to its primary position and the last pair of switch or coupling pins withdrawn to indicate that the rod is disengaged. To prevent this rod C from being turned or revolved too far a pin, *g*, is inserted transversely through it, the point of said pin engaging in the slot *h* of the board A. 85 90 95 100

Other forms of these movable indicating conducting-rods are shown at D and E in the

drawings. D is a square rod with differently-colored faces and provided with pin-holes b, and E is a square hollow rod provided with vertical grooves c, that are of a different color 5 from the rest of the rod, and it is also provided with pin-holes d. These rods D E are connected with telephones through their respective wires G H. The rods D E are also connected, when required, through the termini 10 of the main-line wires, in the manner already described for rod C, by the coupling-pins N N and wire O.

To indicate that the rod D is in use it is turned upward, so as to present an angle to 15 the front, and thus show two faces of different colors; and it is limited in its turning by the engagement of its pin i against a corresponding pin, k, set in the switch-board A. To indicate that the rod E is in use it is made to slide 20 laterally, so that the colored grooves c in its face will be moved from behind the vertical supports B and be exhibited, as shown in Fig. 2.

To indicate that the rod D is not in use it 25 is moved in the opposite direction, so that the colored grooves c will pass under and be hidden by the support B, and the extent of its lateral movement is determined by the pins m m, that are set in the said rod E on either 30 side of one of the braces B.

In a telephone central office or exchange, where many main-line wires converge, these 35 switch movable indicating-rodS are found to be of great utility and convenience. Being arranged in compact and regular order immediately beneath the lines of switches in which the main-line wires terminate, they afford to

the operators in the office most ready means for connecting the various lines of communication, and as the operators can tell at a glance 40 from the positions of the rods whether the rods are in use or not, the work of making and breaking connections between the main-line wires is greatly facilitated.

I do not limit or confine myself to the exact 45 form or position of any of the parts herein described, as they may be varied without departing from my invention.

I am aware that the pins N, with their flexible connecting and conducting wires O, are not, 50 in themselves, new; and I therefore disclaim the same as being my invention.

Having thus described my invention, I claim as new and desire to secure by Letters Patent—

1. A telephone switch-board made substantially as herein shown and described, and consisting of a suitable board carrying one or more movable indicating conducting-rods, with which the telephone-wires connect, as set forth. 60

2. In a telephone switch-board, the movable indicating conducting-rods, constructed and operating substantially as herein shown and described.

3. In a telephone switch-board, the combination, with the telephone line-wire terminals, of the movable indicating conducting-rods, substantially as and for the purpose herein shown and described. 65
